INVENTOR.

Frank L. Antisell.

BY
Cornelia C. Billings
ATTORNEY.

UNITED STATES PATENT OFFICE.

FRANK L. ANTISELL, OF PERTH AMBOY, NEW JERSEY.

ANNEALING FURNACE.

Application filed February 17, 1923. Serial No. 619,619.

To all whom it may concern:

Be it known that I, FRANK L. ANTISELL, a citizen of the United States, and a resident of Perth Amboy, county of Middlesex, State of New Jersey, have invented certain new and useful Improvements in Annealing Furnaces, of which the following is a specification.

The invention relates particularly to a continuous non-oxidizing annealing furnace, and one of the objects thereof is to effect continuous anneal of a sheet or strip of metal, particularly copper, and which will, during the annealing operation prevent oxidation of the metal being treated.

Another object of the invention is to provide an annealing furnace in which the annealing heat is transmitted to the strip of metal being operated upon by means of radiation from a previously heated metal strip forming a conduit wall.

Another object is to provide an annealing furnace so constructed that the heat is applied to the metal to be operated upon at a uniform temperature.

Other objects will appear from the subjoined specification and claims.

In the drawings forming a part of this specification:

Fig. 1 is a longitudinal section of an annealing furnace embodying my invention.

Fig. 2 is a horizontal section of the same on line 2—2 of Fig. 1.

Fig. 3 is a horizontal section on line 3—3 of Fig. 1 showing in elevation a fragmentary view of a coal chute.

Fig. 4 is a section on line 4—4 of Fig. 1.

Fig. 5 is a fragmentary sectional view of the mouth of the conduit through which the strip of metal passes.

In the figures the illustration is conventional but it is to be understood that the walls of the furnace 10 may be made in any suitable way as by means of fireproof brick and concrete.

At each end of the furnace are chambers 11 and 12, the chamber 11 being connected with the grate portion 13 which is provided with suitable grate bars 14 and ash remover 15 upon which the coal C is placed and ash pit 16, the coal being fed into the furnace from the hopper H.

The arrows 20 indicate the direction of the passage of the products of combustion and the heat units from the fire pit 11 to

the chimney 12. The passageways 25 and 26 and 27 are formed within the furnace, the heat units passing from the passageways 25 and 26 to the passageway 27 through openings 28 in the partition walls 30 and 31.

The conduit 40 through which the strip of metal M to be annealed is to pass is constructed upon a copper plate 41 which extends across the furnace and which forms not only the heating element for the annealing operation, but also the floor of the conduit. The copper plate 41 rests at each edge upon shoulders 42 and 43 formed on the inside of the brick walls of the furnace and is further supported by a body of sand S which fills the lower portion of the furnace structure. The top and sides of the annealing conduit are formed by means of a series of sections of cast iron plates 44 provided with downwardly projecting flanges 45 and 46 on each side at the edge thereof, which flanges form supports and rest upon the copper floor and heating plate 41. The conduit is therefore formed by laying sections 44 of these cast iron plates end to end throughout the length of the furnace, one end section projecting outwardly and downwardly into a tank T thus forming a water seal W, in which tank is mounted a guide roller G under which the strip of metal M, which has been annealed, passes to the winding roll R' which receives the annealed metal after it is passed through the furnace from the initial roll R suitably mounted and positioned at the mouth of the furnace.

To preclude the products of combustion from entering the annealing conduit the cast iron sections 44 are covered with fire brick at their sides, as clearly shown in the drawing, and with sand and clay on top. This construction permits the expansion and contraction of the metal without causing a destruction of the furnace construction.

In order to preclude the entrance of air into the annealing conduit the water seal W of the usual type is formed at one end and a pivoted flapper door D of cast iron seals the entrance to the conduit, thus tending to exclude air therefrom and to permit the building up in the conduit of an atmosphere of hot nitrogen gas because of the extraction of the oxygen by the heat of the first metal which passes through the furnace.

By the introduction of pure nitrogen or hydrogen independently generated, the furnace can be started so as to produce bright annealed sheets from the beginning of the operations.

The end of the metal is drawn from the roll R through the annealing furnace by means of a fish wire and it is then extended to the automatic reel R' properly secured thereto for rewinding, the speed of the reel, which may be turned by any known means, being regulated from predetermined temperature readings in the interior of the conduit.

15 By means of this construction the heat transfer from and through the heating chamber, which is filled with the products of combustion of any suitable sort of fuel, heats the copper plate 41 which functions as a conduit member upon which plate is built the conduit from the cast iron sections 44, said conduit of course being made of suitable dimensions to permit a continuous flow of metal to be annealed.

20 25 30 35 40 45 By means of the furnace hereinabove described, I am enabled to continuously anneal strips of metal, preferably copper, without oxidation, the annealing being effected by radiation from the metal wall or walls of the annealing chamber, and at the same time obtain a heat efficiency sufficiently high to result in rapid annealing.

Furthermore, the application of the annealing heat from a previously heated metal 25 wall of copper which has been first heated so that its temperature is uniform throughout, renders the annealing uniform and obviates the tendency to over anneal with a loss due to the elongation of the metal and 40 its resistance to all annealing stress.

Copper annealed by means of the furnace embodying my invention does not scale due to its being exposed to the flame of the fire and it is not therefore necessary to pickle, wash and dry the metal in order to preclude staining which is the usual practice during the operation of annealing in the prior art.

45 As changes of construction could be made within the scope of my invention, it is intended that all matter contained in the above description or shown in the accompanying drawing be interpreted as illustrative and not in a limiting sense.

Having described the invention what I 50 claim and desire to secure by Letters Patent is:

1. Apparatus of the type described which comprises a furnace having a combustion chamber, an annealing chamber, in said furnace surrounded by heat resisting walls and a metallic heat conducting member extending from said chamber into said combustion chamber.

2. Apparatus of the type described which 60 65 comprises a furnace having a combustion

chamber, an annealing chamber extending through said combustion chamber and protected from direct transfer of heat from said combustion chamber and a metallic floor for said annealing chamber extending into said 70 combustion chamber.

3. Apparatus of the type described which comprises a furnace having a combustion chamber, an annealing chamber extending through said combustion chamber and protected from direct transfer of heat from gases in said combustion chamber, a metallic floor for said annealing chamber extending into contact with gases in said combustion chamber and means for sealing the interior 80 of said combustion chamber from the atmosphere.

4. Apparatus of the type described which comprises a furnace having a combustion chamber, an annealing chamber extending through said combustion chamber and protected from direct transfer of heat from gases in said combustion chamber, a metallic floor for said annealing chamber extending into contact with gases in said combustion chamber, a sealing door at the entrance end 85 of said annealing chamber and a water seal at the exit end of the said annealing chamber.

5. Apparatus of the type described which 90 comprises a furnace having a combustion chamber, an annealing chamber extending therethrough and protected from direct transfer of heat from gases in said combustion chamber, and a copper floor for said 100 annealing chamber extending into contact with the combustion gases of said combustion chamber.

6. Apparatus of the type described which 105 comprises a furnace having a combustion chamber, an annealing chamber extending through said combustion chamber, said annealing chamber having a metallic floor extending into said combustion chamber into contact with the hot gases of said combustion chamber and upper walls protected from direct transfer of heat therethrough to the interior of said chamber.

7. Apparatus of the type described which 110 comprises a furnace having a combustion chamber, a flue in said combustion chamber, an annealing conduit extending through said flue and protected from direct transfer of heat from the gases in said furnace, and a metallic plate extending from said annealing conduit into contact with the combustion gases of said furnace.

8. Apparatus of the type described which 115 comprises a furnace having a combustion chamber, a flue in said combustion chamber having inlet ports for the admission of products of combustion from said combustion chamber, an annealing conduit extending through said flue and protected from direct transfer of heat from the gases in said flue,

and a heat conducting plate extending from said annealing conduit into contact with the gases in said combustion chamber.

9. Apparatus of the type described which comprises a furnace having a combustion chamber, a flue in said combustion chamber having inlet ports for the admission of products of combustion from said combustion chamber, an annealing conduit extending through said flue and protected from direct transfer of heat from the gases in said flue, a heat conducting plate extending from said annealing conduit into contact with the gases in said combustion chamber and means for sealing the annealing conduit from the entrance of atmospheric air.

10. Apparatus of the type described which comprises a furnace having a combus-

tion chamber, an annealing chamber extending through said combustion chamber and protected from direct transfer of heat from the gases in said combustion chamber, said annealing chamber being formed of metallic sections, means for protecting the annealing chamber from direct contact with the furnace gases and means for sealing the ends of said chamber from the entrance of air.

11. Apparatus of the type described which comprises a furnace, an annealing chamber in said furnace protected from direct transfer of heat from the furnace gases and metal heat conductors extending from said annealing chamber into contact with the furnace gases.
